CONTAINER CONSTRUCTION

Franz Neuschafer, Rye, N. Y.

Application February 27, 1940, Serial No. 320,987

3 Claims. (Cl. 35—59)

This invention relates to container constructions adapted to contain and display in an improved manner, liquids such for example as preparations for treating the finger nails.

This application is a continuation in part of my copending application Ser. No. 305,766, filed November 24, 1939.

Colored liquid preparations, such as finger nail polishes for example, are customarily sold and displayed for sale in small glass bottles, and generally a great many of the bottles containing respectively slightly varying color shades are displayed together. While to a certain degree, the color of the liquid within each bottle is revealed through the glass, it is difficult for the purchaser to determine in this way the appearance which the color will have in use or the exact shade desired to match a color previously used. Accordingly it is now customary to apply a color name to each bottle and to display corresponding color charts in various forms adjacent the bottles to aid the purchaser in selecting the desired shade. However, the distinctions between the different color shades are quite fine and it is difficult to insure that each bottle will always contain the exact shade intended, and it is difficult to print the color charts so that they will accurately represent each of the slightly different color shades or indicate the appearance which the same will have in actual use.

The present invention offers an improved means for avoiding the above noted difficulties and provides a container which will effectively display the color of the liquid in a manner similar to the appearance of the color shade when applied in use.

Various further and more specific objects, features and advantages will clearly appear from the detailed description given below taken in connection with the accompanying drawing which forms a part of this specification and illustrates merely by way of example a preferred form of the invention. The invention consists in such novel features, arrangements and combinations of parts as may be shown and described in connection with the constructions herein disclosed.

In the drawing Figs. 1, 2 and 3 are front, back and top views respectively of a container constructed in accordance with the invention;

Fig. 4 is a vertical sectional view taken substantially along the line 4—4 of Fig. 3;

Fig. 5 is a top view showing a plurality of the containers made according to the invention and arranged for effective display;

Fig. 6 illustrates the manner in which a plu-

rality of said containers may be stacked for display or closely packed for shipment, and

Fig. 7 illustrates a form of label which may be used for the container in accordance with the invention.

As shown in the various figures, the container may comprise for example a bottle 10 formed preferably of transparent or substantially transparent glass, and having a closure as at 11 of any suitable well-known type. In case this bottle or container is to be used for colored liquid finger nail polish, for example, then one of its walls, preferably a side wall, is integrally formed with a raised portion or protuberance 12, having a curvature and outline such as to substantially simulate a finger nail or a portion thereof. That is, this protuberance in its preferred form may be made of substantially the same size and outline as a finger nail and with a correspondingly smoothly curved surface. Thus the colored liquid will be revealed and attractively displayed through this curved area in a manner closely similar to the appearance of the color shade when applied to the finger nails.

As above indicated, it is difficult for the purchaser to accurately determine what the appearance of the color shade will be in actual use merely from viewing the color through the ordinary walls of a glass bottle. That is, such walls are of varying thickness and curvatures at different points, the surfaces are such as to generally give irregular reflections of light, and will not have curvatures corresponding to those of the finger nail, and accordingly light reflected therefrom and shadows thereon will not give the same appearance as the color when applied to the nails. The large areas or masses of the color observed through the ordinary walls of a bottle will further prevent the purchaser from appreciating the appearance which it will have in use. On the other hand, by the use of the above described protuberance simulating the finger nail, an area of color may be exposed which quite accurately corresponds to the treated finger nail both as to extent and curvature. Consequently upon viewing the protuberance with the curved body of colored liquid therein, the purchaser is able to accurately check its appearance and shade with one of her finger nails, and with definite assurance that the liquid being purchased is the identical liquid with which comparison is made.

In order to accurately reveal the appearance of the color area, the glass at the protuberance 12 is preferably made relatively thin so as to bring the colored liquid close to the observed surface

and also the glass at these areas is preferably of substantially uniform thickness so that the outer convex surface and the inner concave surface will substantially correspond in curvature.

As further shown in Figs. 1 and 3, the protuberance 12 may be formed upon a convexly curved area 13 forming a substantial part of the front surface of the bottle and extending from top to bottom thereof. This area 13 may for example conform to the curvature of a cylinder and affords a place for effective and prominent display of a label 14, such for example as shown in Fig. 7. As indicated in Fig. 7, this label may have an opening or cut-out portion 15 conforming to the shape of the protuberance 12 and serving to prominently outline the same, thus enhancing the natural appearance of the simulated finger nail. The lower portion of the label may also be creased or printed with a representation of a portion of a finger as at 16, further contributing to the natural appearance of the nail polish as exhibited through the transparent protuberance. It will be further noted that the cylindrically curved area 13 on which the label is placed also serves to give the finger representation 16 a more natural appearance.

As shown in Figs. 2 and 3, the side walls of the container as at 17 and 18 may preferably be formed at angles so that the same tend to converge rearwardly. If the planes of these side walls are for example substantially at 45° with the approximate plane of the front walls as shown, then four of the bottles may be so placed on display as to form an enclosure as in Fig. 5. With this arrangement a group of bottles, each containing different colors, may be effectively displayed with the simulations of the finger nails facing outwardly, and thus displaying one color in each direction. As shown in Figs. 3 and 5, the front faces of the bottles at each side of the main part of the label, may be curved somewhat as at 19 whereby the appearance of the display as a whole is enhanced and made more nearly circular. At the same time these curvatures permit the color shades in adjacent bottles thus displayed to be more effectively compared by the observer. That is, due to the curvatures 19, the adjacent front surfaces of two adjacent bottles instead of coming together at a right angle, are more nearly merged with each other, thus facilitating a direct comparison of the two colors therein.

As shown in Figs. 2, 3 and 4, the rear surface of the container may preferably be formed with a depression as at 20, of cylindrical curvature and extending from top to bottom of the bottle. It will be noted that this depression is such as to accommodate the convex area as at 13 on another bottle, whereby numerous bottles may be securely stacked for display or shipment, one upon another, as in Fig. 6. Hence, notwithstanding the curvatures of the front surface of the bottle and the protuberances thereon, the bottles may be effectively stacked without danger that one will slide off from the bottle beneath and become broken, and without danger of breaking or scratching the protuberances 12.

As more clearly appears in Figs. 2 and 4, the depression 20 may also include a further depression as at 21 conforming as to depth and shape substantially to the protuberance 12 on the face of the bottle. Thus, when the bottles are stacked, the protuberance 12 will engage a depression 21 on the adjacent bottle and thus fur-

ther tend to anchor the bottles in properly stacked relationship. The area below the depression 21 as at 22 may preferably be so cast as to represent a portion of a finger. When the buyer desires to inspect the product under conditions of actual use, she may conveniently place the back of her finger upon the areas 21 and 22, while from the front side of the bottle she inspects the appearance of the colored nail simulation 12 in comparison, for example, with colors previously used on her other finger nails.

In order to demark and outline the areas 21 and 22, the remainder of the rear and side surfaces of the bottle may be cast with a ridged or somewhat corrugated formation as at 23, which will also tend to prevent the bottle from slipping off the observer's finger when applied as above described. The corrugations or ridged formations at the sides of the bottle will also permit more or less engagement of such side walls with the side walls of adjacent bottles when on display, as in Fig. 5, thus tending to retain the display against displacement. It will be noted that each side of the depression 20 terminates in an outstanding ridge. This construction has a particular advantage in combination with the curved display areas such as at 21, 22 for the following reasons. The bottle is not ordinarily quite completely filled with liquid when sold, and any air bubbles or air spaces will naturally rise to the upper surface of the liquid. Thus if the bottle is displayed while on its side, with the simulation facing upward, irregular air spaces, interrupting the body of the colored liquid, will show through the glass side wall. However, with the construction here shown in Fig. 2, the air will accumulate within the above mentioned ridges, thus leaving the liquid as displayed through the areas 21, 22, uninterrupted and unmarred by bubbles or the like. That is, the portions adjacent the areas 21, 22 are directed inwardly of the bottle so that air bubbles contacting these portions of the wall will be deflected or held away from areas 21, 22.

As shown in Figs. 1 and 4, the protuberance 12 at its lower edge may be somewhat recessed to correspond to the so-called "moon" area of the finger nail. And as appears in Fig. 7, the portion of the label 14 bearing the representation of the finger 16 may be extended up somewhat to cover this "moon" area, the somewhat recessed portion of the protuberance 12 providing a space for receiving this extended portion of the label and providing for a relatively smooth merging of this slightly curved label area with the adjacent curved areas of the protuberance. Since the "moon" area normally has a compound curvature, as do the remaining nail areas, the paper label if applied to this area would normally split or tend to tear, but the slight recessing of this area of the protuberance as shown is sufficient to avoid such a result. Thus this area of the label will serve to cover the "moon" area without tearing or splitting, and prevent the color of the liquid in the bottle from showing through at this point. Since it is customarily not the practice to apply the colored nail polish to the "moon" areas, the covering of these areas by the label enhances the realistic nature of the display of the remaining colored areas of the nail simulation, while the label as shown in Figs. 1 and 7 may be so decorated at this area as to give a realistic contrast between the "moon" area, the colored nail areas, and the remaining finger areas.

While the invention has been described in detail with respect to particular preferred examples, it will be understood by those skilled in the art after understanding the invention that various changes and modifications may be made without departing from the spirit and scope of the invention, and it is intended therefore in the appended claims to cover all such changes and modifications.

What is claimed as new and desired to be secured by Letters Patent is:

1. A glass container adapted to contain liquid preparations for treating the finger nails, a wall of said container being formed with an integral substantially transparent protuberance having a curved surface and an outline such as to substantially simulate a finger nail in vertically extending position on said wall, and whereby the color of the liquid in the container is revealed therethrough in a manner similar to the appearance of the color when applied to the finger nails, and an opposite wall of said container being constructed and arranged with a depression adapted to receive a similar protuberance on another container, and also sufficiently extended vertically to provide a depression to embrace the back end portion of the finger of a user when viewing the appearance of the liquid in said protuberance.

2. In combination, a glass container adapted to contain liquid preparations for treating the finger nails, a wall of said container being formed with an integral protuberance, substantially transparent and having a curved surface and an outline such as to substantially simulate a finger nail, and whereby the color of the liquid in the container is revealed therethrough in a manner similar to the appearance of the color when applied to the finger nails, and a label secured to said wall, said label having an opening with edges forming an outline for and demarking said protuberance, and a representation of a finger on said label in association with said opening.
3. A container constructed in accordance with the foregoing claim 2 and in which said protuberance is formed on a vertically extending outwardly convex area of the wall, said area including the area bearing said representation of a finger and being formed integral with the protuberance and the remainder of said wall, and an opposite wall of the container, on its outer surface, being constructed and arranged with a vertically extending concave area for embracing the back end portion of the finger of a user when viewing the appearance of the liquid in said protuberance.
